(57) CLAIM

The ornamental design for a protection cover for electronic devices, as shown and described.

DESCRIPTION

FIG. 1 is a perspective view of a protection cover for electronic devices showing my new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The dotted line showing the rest of the protection cover is for illustrative purposes only and forms no part of the claimed design.
